UNITED STATES PATENT OFFICE.

CAID H. PECK, OF ATHENS, PENNSYLVANIA, ASSIGNOR TO INGERSOLL-RAND COMPANY,
OF NEW YORK, N. Y., A CORPORATION OF NEW JERSEY.

FLUID-MOTOR DRILL.

1,212,998.

Specification of Letters Patent. Patented Jan. 16, 1917.

Application filed March 7, 1912. Serial No. 682,173.

To all whom it may concern:

Be it known that I, CAID H. PECK, of Athens, in the county of Bradford, and in the State of Pennsylvania, have invented a 5 certain new and useful Improvement in Fluid-Motor Drills, and do hereby declare that the following is a full, clear, and exact description thereof.

The object of my invention has been to 10 provide a fluid motor drill, and particularly a pneumatic drill, which shall have, among others, the advantages of being light in weight, of small dimensions, and of a comparatively small number of parts, and 15 which shall have other advantages, more particularly referred to hereinafter, and to such ends my invention consists of the fluid motor drill hereinafter specified.

While my invention is capable of embodiment in many different forms, for the purpose of illustration I have shown only one form thereof in the accompanying drawings, in which—

Figure 1 is a vertical section of a drill 25 made in accordance with my invention; Fig. 2 is a horizontal section of the same; Fig. 3 is a plan view of a tool used for detaching the plates used for holding the connecting rods attached to the pistons; Fig. 4 is a plan 30 view of one of said plates; Fig. 5 is a sectional view showing the valve arrangements; Fig. 6 is a horizontal sectional view of one of the valves; Fig. 7 is a horizontal section of the same taken in another position; Fig. 8 is a vertical section of one of the valves showing two of the cylinders also 35 partly in section; Fig. 9 is a vertical section through the inlet ports; and Fig. 10 is a diagram showing the operation of the 40 engine.

In the accompanying drawings, I have illustrated one embodiment of my invention, which is the best embodiment known to me, but such embodiment is to be regarded as typical only of many possible embodiments, and my invention is not to be limited thereto.

The illustrated embodiment is of the type in which four single-acting cylinders and 50 pistons drive a double crank shaft, the cylinders being arranged in two pairs sub-

stantially at right angles to each other so as to avoid a dead center, and the drill being driven from said crank shaft. In the illustrated embodiment, I provide a main 55 casing 1, having upper and lower cylinders 2 and 2^a in the same radial plane, and having a similar pair of cylinders 3 and 3^a, respectively, in a radial plane substantially at right angles to the first mentioned pair. 60 Pistons in these cylinders drive a double crank shaft 5, which is journaled in upper and lower bearings 6 and 7, the latter being preferably of the ball type and being preferably clamped between the main casing 1, 65 in which the cylinders are formed, and a crank shaft casing 8.

Each cylinder contains a single-acting piston 9 having a spherical socket 10 in which is seated a ball 11 on one end of a 70 connecting rod 12 whose opposite end engages one of the cranks. The ball 11 is held in its socket 10 as by a split washer 13, the latter being sprung into a groove 14 within the trunk piston. For convenience, the 75 washer may be provided with holes 15 on each side of the split, which may be engaged by the prong 16 of a tool like a pair of pliers, which is shown in Fig. 3, so that by means of said tool the said holes may be forced toward each other and the washer contracted so as to free it from the groove and piston. As the pressure of the air forces the piston toward the rod on the outer stroke and the pressure of the rod 80 forces the piston back on the in-stroke, the tendency is always to force the rod and piston together and thus to force the ball into its socket so that the simple split washer 85 fastening admirably serves its purpose.

In order to enable the connecting rods from the two cylinders at the same level to engage the same crank, and especially to make a construction in which no parts can work loose, and one which shall be simple, 95 the following construction is provided: Each connecting rod 12 is provided with a sleeve 12^a, which is preferably formed of one piece and integral with the connecting rod. Each sleeve is preferably slotted to provide two 100 separated rings 12^b and 12^c, respectively, so that the rings of the two connecting rods en-

gaging the same crank-pin may be placed alternately with one ring of each sleeve occupying the slot of the corresponding sleeve. This arrangement permits a wide bearing of the sleeves along the crank-pin, and yet permits that the two connecting rods shall be substantially opposite the center of the crank-pin. A steel "liner", or bushing, 12^a is placed within the sleeves which surround the single crank-pin, such liner having the same length as the crank-pin, and a series of rollers 12^b is placed between the crank-pin and the liner thus forming an effective roller bearing. The crank-cheeks 12^c on the rear or center side of the crank-pin are wide enough to overlie the connecting rods and the liner and to prevent their displacement along the crank-pin. The rollers are put in place through a hole 12^d formed in the crank, such hole being normally closed by a screw 12^e. A wire 12^f, or other form of lock, engages the screws and prevents their turning after they had been properly screwed home. The said wire is sprung into holes drilled 25 in each of the said screws.

In assembling the cranks and their yokes (formed by their rings) on the crank-shaft, the yokes are first worked along over the crank-shaft from one end thereof to the proper crank-pin, and then the rollers are afterward put in place, after which the screws 12^e are screwed home and are fastened by the wire 12^f. I prefer to make the screws long enough so that they will project through the crank-cheeks, and then to grind them off flush with such cheeks in order that they may form a smooth bearing for the ends of the rollers as they pass around.

It will be seen that the construction of my connecting rods with the crank-shaft is exceedingly simple and yet very efficient. There is no part to come loose, the parts are very simple to manufacture, and yet the bearings are long and of ample area.

The line of division between the crank-shaft cap 8 and the main casing may take any direction so long as it passes through the crank-shaft bearings. By making a division through such bearings it is only necessary to remove the said cap in order to be able to take not only the crank-shaft out of its bearings, but all of the connecting rods and their pistons, and this without any further disassembling than taking off such crank-shaft cap. This construction is a very great advantage for purposes of cleaning and repairing and also makes it unnecessary to provide removable cylinder-heads for the cylinders, there being no necessity for opening the end of the cylinders opposite the crank-shaft.

The method which I have illustrated, of securing the crank-shaft cap to the main casing, is as follows: On the upper end of the

cap and casing are formed parts of an angular boss 29, which, in this instance, is threaded and upon which is screwed a cap 30. At the lower end of the crank-shaft a gear-case or cap 31 is bolted to the casing 70 and to the crank-shaft cap and thus secures the two together.

In order to secure the ball bearings to the shaft, so that the ball bearings will stay assembled and be carried with the shaft in 75 taking the shaft out of the casing, I provide the upper end of the crank-shaft with a nut 32 which overlies the inner ball race of the upper bearing, and on the lower end of the crank-shaft I form the pinion 33 so 80 that it overlies the lower ball race, the pinion being held on to the crank-shaft by a screw 34 (and of course a key). The usual handle 35 may be screwed into the crank-shaft cap.

It has been one of my objects to make a valve gearing which is exceedingly simple and efficient. The valves, as illustrated, consist each of a cylindrical plug 36 having a pinion 37 formed on its lower end, the 90 valve-body being seated in a bushing 38 and forming a journal both for itself and for the pinion. The pinion bears against the lower end of the bushing, and the lower end of the valve-body bears against the gear-case 31, so that to put the valve-body and pinion in place it is only necessary to drop the valve-body into the bushing and secure the gear-case in place. The upper end of the bore in which the bushing and valve are 100 seated is closed as by a cap 39. Motion is transmitted to the pinions 37 from the crank pinion 33 by a gear 40 mounted on the drill spindle, as later described. Each bushing has a groove 41 in its outer periphery which is in communication with a live air duct 42 from the throttle. The said groove 41 is cut through the bushing at one point to form a live air port 43, that communicates alternately with live air grooves 44 and 45 110 formed in the periphery of the valve-body. The groove 44 extends from the live air port downward to carry live air to the port 46 of the lower cylinder of the pair, for instance, the cylinder 3^a. The groove 45 extends upward to carry live air to the port 45 of the upper cylinder of the pair, for instance, the cylinder 3. For the purposes of exhaust, upper and lower ports 48 and 49 are 115 cut through the valve-body to communicate with an interior bore, the air escaping from such bore to the upper end 50 of the bore in which the bushing and valve-body are seated, and thence by a duct 51, which communicates with the upper port 54 from the 120 throttle valve.

The cylinders have piston exhaust ports 51^a which open from the side of each cylinder into the space inclosed by the casing, and air exhausted through such ports es- 130

apses from the casing through holes 51^b and preferably under hoods 51^c which directs the air downward toward the throttle.

In the operation of my valve, the live air in the groove 41 passes through the live air port 43 ready to enter the grooves 44 or 45 in the valve-body as the valve rotates. The groove 44, when communicating with the port 43, carries live air to the port 47 of the upper cylinder, forcing the piston forward. At the same time the port 49 connects with the port 46 of the lower cylinder, allowing exhaust through the port in the interior of the body of the valve, the air escaping through the port 51 and through the throttle valve. The continued rotation of the valve brings the groove 45 into communication with the port 43, and carries live air to the port 46 of the lower cylinder, at the same time permitting the upper cylinder to exhaust through the port 48. The piston port 51^a is uncovered by each piston as it approaches the end of its stroke, and most of the exhaust occurs through such ports, the trapped air only being exhausted through the ports 46 and 47, and the ports 48 and 49 in the valve. The air passing through the piston ports 51^a expands into the valve casing, cooling the casing and then passes out through the openings 51^b and beneath the hoods 51^c to the outer atmosphere.

It will be observed that the live air groove 41 in the bushing is formed in its outer periphery and that such groove only communicates with the valve-body through the live air port, which extends but a small fraction of the way around the circumference of the valve-body. This construction reduces to a minimum the leakage between the valve-body and the bushing. In previous constructions the live air groove in the bushing has been on the inner periphery of the bushing, and leakage, therefore, has occurred throughout the entire circumference of the valve-body, leakage flowing toward whichever cylinder may be exhausting at one time or the other. This is a very substantial advantage of my valves.

In order to control the supply of air to the valves, and to enable the drill to be readily reversed in motion, I provide a throttle and handle mechanism as follows: A valve stem 52 is fitted in a sleeve or bore 53 formed in the casing 1 and is provided with an upper duct 54 and a lower duct 55. The lower duct communicates by lateral holes with the live air ducts 42, the upper duct 54 communicates by a vertical passage 56 with the exhaust ducts 51. The passage 55 opens laterally through the periphery of the valve stem forming a port 57 while the passage 54 forms a corresponding and opposite port 58; the hose connection 59, having the usual sieve therein, is screwed on the outer end of the valve-stem and communi-

cates with a central passage 60 in such stem, such passage opening through the periphery of the valve-stem by ports 61 and 62, which are respectively adjacent to the ports 57 and 58. A rotatable valve sleeve 63 is journaled on the valve-stem, preferably on a tapered journal, and is held closely upon the taper by a spring 64, which bears against said sleeve at its forward end and against a shoulder in a cylindrical sleeve 65 on the valve-stem; the sleeve 65 has a by-pass 66 formed therein by which communication may be effected between the ports 61 and 57, or between the ports 62 and 58, according to the position of the sleeve 63 upon its journal. When communication is effected between the ports 61 and 57, the drill is driven normally forward in the manner previously described. When, however, the sleeve 63 is rotated to a position in which its by-pass affords communication between the ports 62 and 58, then the live air passes through what are normally the exhaust ducts, namely, the ducts 56 and 51, into the interior of the valve and the ports 48 and 49 then become the live air ports of the valve while the ports 44 and 45 act as exhaust ports and send the exhaust air through the groove 41 and duct 42 to the passage 55, and thence out through the port 57 to the atmosphere.

In order to control the movements of the sleeve 63, so as to make the same drill either reversible or non-reversible, it is simply necessary to permit rotation of said sleeve through half a circle, or to limit it to $\frac{1}{4}$ thereof. I accomplished this by a single construction in the following simple manner: I formed two holes 52^a and 52^b in the valve-stem 52, in order that a pin 52^c may be driven into either of said holes to limit the rotatable movements of the sleeve 63, by striking shoulders formed on the said sleeve. I preferably form the said shoulders by milling away the forward edge of the said sleeve for approximately the distance of a semi-circle, as shown at 63^a. The said shoulders and the said pin-holes are so formed, relatively to each other, that when the pin is driven in the hole 52^b the throttle sleeve in one extreme position has its by-pass 66 in communication with the live air port 57, and in the other extreme position, in communication with the exhaust port 58, thus enabling the drill to be reversed by throwing the sleeve into either of the two said positions. When the pin is in the hole 52^a the extreme positions of the sleeve are ones in which the by-pass is not in communication with either port, the by-pass only in an intermediate position being in communication with the live air port 57, the pin preventing the by-pass from being thrown into communication with the exhaust port at all. This simple and convenient construction enables my drill to be manufactured in large

quantities and then to be sold either as reversible or non-reversible drills, the only change necessary being to drive the stop-pin in one or the other holes 52^a or 52^b. It will 5 thus be seen that simply by rotating the valve-sleeve 63 from one position to a diametrically opposite one, my drill can be caused to rotate backward.

My drill, although reversible, has the unusual quality of being practically as powerful when running backward as it is when running forward. In order to illustrate this, I have shown in Fig. 10 a diagrammatic representation of the cycle taking 10 place in the engine, when it is running forward. The piston, when the machine is running right-handed, takes live air for 120 degrees of the crank revolution. The live air port then closes and the air expands for 15 about 25 degrees, after which the cylinder or piston exhaust 51^a exhausts for approximately 65 degrees of the crank revolution. Most of the air is exhausted at this time and what remains and is trapped escapes through 20 the ports 46, 47, 48 and 49 and passes to the throttle, the said ports remaining open to 25 the end of the stroke.

When the machine is reversed the diagram is exactly the opposite and the machine 30 is practically as strong as when moving forward or right-handed, except for the fact that during the 25 degrees of the crank revolution, when expansion occurred on the forward rotation, compression occurs on the 35 reverse rotation. It will be understood that the valve diagram can be largely varied and that the one illustrated is only to be taken as typical, the advantage gained being by 40 the use of the cylinder exhaust port 51^a in its relation with the other parts.

The manner in which the drill spindle, which carries the drill, is mounted in my said machine and in which it is driven, is as follows: The gear case 31 is provided with 45 a sleeve 67 preferably having a bushing 68 therein, which bushing forms the sole journal for the drill spindle or chuck 69. The said drill spindle is formed with a shoulder 70 at its upper end, on which is seated the lower race 71, of a ball-bearing whose upper race 72 rests against the lower end of 50 a hollow screw 73. The said screw is provided with a cylindrical portion 74 which is received in a bore in the main casing and 55 which has a flange 75 that is adapted to overlie and rest against the casing, a key 76 being provided to prevent rotation of the screw in the bore. The shank of the screw 73 is preferably extended downward in the 60 form of a sleeve 77, which extends within the upper end of the drill spindle. The drill spindle is provided with studs 78 which are carried on a disk or spider-arm 79 on the drill spindle, the said studs having pinions 65 80 journaled thereon. These pinions mesh

with teeth forming a pinion 81 on a sleeve 82 which is secured to and preferably integral with the gear 40 before mentioned, by which motion is communicated from the crank pinion 33 to the valve pinions. The lower end of the gear case is preferably provided with a stuffing-box 83 so that the gear case, and, if desired, the entire casing of the drill, may be filled with oil. 70

The screw 73 is engaged by an internally threaded sleeve 84, having near its upper end a hand-wheel 85, and also having a hardened center 86 screwed into the upper end of said sleeve. The said center 86 is preferably provided with a long shank 80 which is threaded for some distance below its hardened point so that the shank may be screwed out beyond the sleeve and thus lengthen the height of the hardened center above the drill, if desired. The shank of the center 86 is also preferably extended 85 downward, through the hollow screw, and into the drill socket 87 of the drill spindle so that, when the sleeve 84 is screwed to its lowest position, the said shank will strike 90 the butt end of the drill and loosen it in the socket. 90

The operation of the drill carrying and driving mechanism is as follows: The crank shaft rotates the crank pinion 33, which rotates the gear 40, causing the pinion 81 to rotate the pinions 80, and these latter are thus caused to travel like planets around the axis of the drill spindle, carrying the spider arms or disk 79 and thus rotating the drill spindle at a reduced rate of speed. When it is desired to feed the drill forward, or in other words, to force it into the work, the hand-wheel 85 is rotated in such a way as to unscrew the sleeve 84 on the screw 73 100 and thus to cause said sleeve to rise (so to speak) and to carry upward with it the hardened center 86, or to state it differently, this operation causes the screw 73 to be forced downward and by its pressure on the 105 ball-race to force the drill spindle downward. 110

It will be observed that my drill spindle is controlled entirely by the single journal bearing formed in the sleeve 67, its thrust 115 being taken by the ball-bearing. This means that it is only necessary to form a single journal-bearing to contain and guide my drill spindle and that the difficult operation of forming two journal bearings exactly in line with each other, and especially two such bearings in two separate parts, is avoided. It will also be observed that the thrust of 120 my drill is directly communicated to the screw feed mechanism and is not transmitted 125 to the casing and therefore does not strain such casing. It will also be observed that the gearing for reducing the speed of the crank-shaft to that of the drill is exceedingly simple, and that the same gearing 130

serves to drive the valves. It is further to be noted that all the gearing may be uncovered by simply removing the gear-case and that then each part of such gearing and both valves may be taken out without unfastening any more parts. It will also be noted that my arrangement of crank-shaft bearings and gearing is compact; that my machine has a relatively small height and can be gotten into cramped places, which are inaccessible to larger drills, and yet that the vertical reach of my drill can be increased, if desired, by simply unscrewing the center 86 so as to cause it to project higher than the sleeve 84. This decrease in vertical dimensions results in a corresponding decrease in the weight of the machine.

A further advantage of the illustrated embodiment of my invention may be mentioned 20 as follows: The causing of the exhaust air to escape into the central casing cools the entire drill and tends to prevent the considerable rise in temperature, which would otherwise occur.

25 I claim:

1. In a fluid pressure engine the combination of a casing, a crank-shaft having bearings therein, a plurality of sets of cylinders radiating from said crank-shaft, and pistons having connections with said crank-shaft, said casing being divided substantially through said bearings, said casing having a cap inclosing the ends of the divided casing.

2. In a fluid pressure engine, the combination of a casing, a crank-shaft having bearings therein, a plurality of sets of cylinders in said casing radiating from said crank-shaft, said sets forming an angle to each other, and pistons having connections with 40 said crank-shaft, said casing being divided through said bearings and across said median line of said angle, said casing having a cap inclosing the ends of the divided casing.

3. In a fluid pressure engine, the combination of a casing, a crank-shaft having bearings therein, a plurality of cylinders in said casing radiating from said crank-shaft and forming an angle with each other, and pistons and connections with said crank-shaft, 45 said casing having a division substantially

through said bearings and outside of said angle, said casing having a cap inclosing the ends of the divided casing.

4. In a fluid pressure engine, the combination of a casing, a crank-shaft having bearings therein, a plurality of cylinders in said casing radiating from said crank-shaft and forming an angle with each other, and pistons and connections with said crank-shaft, 55 said casing being divided on a line passing through said bearings and substantially perpendicular to the median line of said angle, said casing having a cap inclosing the ends of the divided casing.

5. In a fluid pressure engine, the combination of a divided casing, a crank-shaft having bearings therein, cylinders in said casing radiating from said crank-shaft and at an angle to each other, said casing having a cap covering said crank-shaft bearings and 60 inclosing the ends of the divided casing.

6. In a fluid pressure engine, the combination of a divided casing, a crank shaft having bearings therein, cylinders in said casing radiating from said crank shaft and at an 65 angle to each other, said casing having a cap inclosing the ends of the divided-casing.

7. In a fluid pressure engine, the combination of a casing, a crank shaft having bearings therein, cylinders in said casing radiating from said crank shaft and at an 70 angle to each other, said casing having a cap covering said crank shaft bearings and also acting as a gear case.

8. In a fluid pressure engine, the combination of a divided casing, a crank shaft having bearings therein, cylinders in said casing radiating from said crank shaft and at an angle to each other, said casing having a 75 cap covering said crank shaft bearings and also acting as a gear case, said casing having another cap covering bearings of said crank shaft and inclosing the ends of the divided casing.

In testimony that I claim the foregoing I have hereunto set my hand.

CAID H. PECK.
